United States Patent Office

Des. 189,333
Patented Nov. 22, 1960

189,333

CHARGE PLATE CASE

Robert John Hayden, 2072 Ronald,
White Bear Lake, Minn.

Filed Jan. 8, 1959, Ser. No. 54,083

Term of patent 3½ years

(Cl. D87—3)

FIG. 1.

FIG. 2.

FIG. 3.

FIG. 5.

FIG. 4.

I claim:

The ornamental design for a charge plate case, as shown.
